UNITED STATES PATENT OFFICE.

ALFRED C. STACY AND WALLIS STACY, OF BLACKEY, VIRGINIA.

HANDSAW-FILING STAND.

Application filed May 21, 1925. Serial No. 31,831.

The invention relates to hand saw filing stands, and has for its object to provide a device of this character comprising a horizontally disposed elongated seat, preferably supported on three legs and a saw clamp carried by the stand above and to one side of the seat for the reception of a saw that is to be sharpened. The seat allows the operator to be seated during the saw filing operation, and to assume a comfortable natural position in relation to the saw during the sharpening operation.

A further object is to provide one side of the seat with upwardly extending arms to which a horizontally disposed bar is attached, and which horizontally disposed bar is provided with clamping members for clamping and holding a saw in a vertical plane.

20 The ends of the horizontally disposed bar form arm rests for the left arm of the operator during a filing operation.

With the above and other objects in view, the invention resides in the combination and arrangement of parts as hereinafter set forth, shown in the drawing, described and claimed, it being understood that changes in the precise embodiment of the invention may be made within the scope of what is claimed without departing from the spirit of the invention.

In the drawing:—

Figure 1 is a side elevation of the stand. Figure 2 is a top plan view of the stand.

35 Figure 3 is an end elevation of the stand.

Referring to the drawing, the numeral 1 designates a horizontally disposed elongated seat, one end of which is provided with a single supporting leg 2, and the other end with spaced supporting legs 3, therefore it will be seen that the device is supported on three legs, consequently no matter what the unevenness of the floor or surface on which the device is placed, all of the legs will engage the floor or surface and rigidly support the stand without wobbling. One end of the seat 1 is provided with an upwardly extending clamp supporting arm 5, and the other end of the seat is provided with an upwardly extending arm 6, which arm is connected to the arm 5 by a horizontal bar

7, which supports the saw clamp 8, above the seat 1. Bar 7 is above the seat 1, therefore it will be seen that the operator may place one leg under the bar when using the device, 55 and the other leg on the outer side of the seat 1 and assumes a position where the ends 7^a of the bar 7 may be used as arm rests for the arms during the filing operation, and at the same time the other arm will be positioned for filing the teeth 9 of the saw 10 at a natural angle, other than a right angle.

The rear end of the bar 7 is further braced by means of an angularly disposed bracket 11, which is secured at 12 to the end of the 65 bar 7, and at 13 to the end of the seat 1, therefore it will be seen that the bar with its clamp 8 carried thereby is thoroughly braced during the saw filing operation.

From the above it will be seen that a saw 70 filing stand is provided, which is simple in construction, provided with an elongated seat on which the operator may sit during the sharpening operation, and the operator may easily move longitudinally on the seat 75 as the tooth filing operation progresses, and in any position on the seat the operator will be in the same relative position in relation to the saw blade at all times during the filing operation.

80 The invention having been set forth what is claimed as new and useful is:—

A saw supporting bench comprising an elongated horizontally disposed seat, supporting legs for said seat, vertically disposed 85 arms carried by one side of said seat adjacent its end, a horizontally disposed bar connected to said arms and disposed to one side of the seat and spaced a substantial distance above the same whereby an operator's legs 90 will pass under the bar, upwardly extending clamping jaws carried by said bar in substantially the same vertical plane as the bar, said clamping jaws being shorter than the bar and terminating spaced from the ends of 95 the bar, thereby allowing the ends of the bar to be utilized as arm rests during a saw sharpening operation.

In testimony whereof we affix our signatures.

WALLIS STACY.
ALFRED C. STACY.
